DISCONNECTIBLE TRANSFER MECHANISM
FOR SETTABLE REGISTERSFrancis J. Rouan, Stamford, Conn., assignor to
Pitney-Bowes, Inc., Stamford, Conn., a corpora-
tion of Delaware

Application March 4, 1949, Serial No. 79,565

3 Claims. (Cl. 235—133)

1

This invention relates to the means employed in effecting the setting of registered numeral wheels of a value registering unit of the type particularly provided in a postage printing and registering device, associated with a machine more commonly known as a metered mail machine.

In a postage printing and registering device, selected variable values are adapted to be printed along with a postage stamp design and other data, and the value printed is adapted to be accumulatively registered in numeral wheels of a registering device. Two registering units are usually provided, one wherein each value printed is added to the previous total value, and one wherein each value printed is subtracted from the previous total. It is with regard to the subtracting register that the present invention is particularly applied.

When a postage printer is to be placed in service, the numeral wheels of the subtracting register are set by an authorized post office official to the amount of cash received, thus establishing a prepaid credit and conditioning the machine for use until the credit value has been reduced to a predetermined amount. Through suitable lock-out means, the printing of a stamp is prevented when the remaining balance becomes less than the highest value which it is possible to print. After a lock-out occurs, the printing and registering unit is again returned to the post office for resetting of the numeral wheels of the subtracting register to place a new credit therein in the amount desired.

In effecting the latter setting operation, each numeral wheel must be free for individual manipulation, and inasmuch as the several numeral wheels are joined by connecting tens transfer elements, means is provided for simplifying disconnection to permit the numeral wheels to be rotated for the setting of the prepaid value therein.

It is the principal object of the invention therefore, to provide means for freeing each numeral wheel from any intermediate connection with an associated numeral wheel of higher or lower order, when a setting of a credit in said numeral wheels is to be effected.

It is another object to effect disconnection of tens transfer elements normally connecting a numeral wheel with a numeral wheel of higher order, by effecting lateral adjustment of a pinion associated with the tens transfer elements.

With the above and other objects in view, which will appear as the description proceeds,

2

the invention resides in the combination and arrangement of parts and in the details of construction hereinafter described and claimed, it being understood that various changes in the precise embodiment of the invention herein disclosed may be made within the scope of what is claimed without departing from the spirit of the invention.

A preferred embodiment of the invention is illustrated in the accompanying drawings, wherein:

Fig. 1 is a plan view showing a portion of a subtracting numeral register wheel structure of a postage printing and registering device;

Fig. 2 is a sectional view taken on the line 2—2 of Fig. 1, and further includes a portion of the casing enclosing the registering mechanism;

Fig. 3 is a sectional view through a numeral wheel, taken on the line 3—3 of Fig. 1; and

Fig. 4 is an exploded perspective view of the tens transfer pinion structure.

Referring now to the drawings in detail, numeral wheels 10 are rotatively mounted upon a shaft 11, which shaft is suitably supported in side frames 12, one wall of which is indicated in Fig. 1. Intermediate supporting walls are also provided as indicated at 13—13. Said numeral wheels 10 preferably include internal differential mechanism of the type disclosed in a patent to Hopkins et al. 1,281,163. Said differential mechanism includes two sun gears 14—14a which rotate freely on both the shaft 11 and within suitable bores 14b—14c respectively in either side of each numeral wheel 10.

Each sun gear 14—14a has a planetary gear 15—15a respectively meshing therewith, which planetary gears 15—15a mesh together and are supported on suitable pins 15b—15c respectively carried by the numeral wheel, as shown in Figs. 1 and 3. Each of the sun gears 14—14a further has a spur gear 16—16a respectively joined therewith, the gear 16 being the driven gear, driven by an actuator gear 17, associated with the values printed, and the gear 16a being driven from a tens transfer mechanism.

Said tens transfer mechanism comprises a compound pinion structure generally indicated at 18, Fig. 1, and includes a Geneva pinion 19, having a splined extension 21, and a transfer pinion 22, having an internal splined portion 23, which is adapted to have a sliding fit on the splined extension 21. The Geneva pinion 19 is adapted to cooperate with a Geneva toothed portion 24 of the numeral wheel 10, and the

transfer pinion 22 is adapted to mesh with the spur gear 16a. Hence, rotation of a numeral wheel through a tens transfer position will effect rotation of the Geneva pinion 19 and transfer pinion 22, to thereby provide rotation of spur gear 16a of the numeral wheel of next higher order.

The Geneva pinions 19 are mounted upon a shaft 25, which shaft is suitably supported parallel to the shaft 11 within the side walls of the frame structure 12. The Geneva pinion structure 19-21 is confined between side walls 26-26 of shaft bracing portions 27 extending from a cross bar 28, supported between the walls of said frame structure 12.

Fingers 29 are pivotally mounted in spaced relation upon a rod 31, which rod is supported between the walls 12, parallel to the shaft 11. Each finger 29 is adapted to block axial movement of the pinion 22, when the gear 16a and transfer pinion 22 are in an operative meshed position and the finger 29 is in the position indicated in the right hand portion of Fig. 1, and the full line position of Fig. 2. When a prepaid credit is to be set in the numeral wheels 10, all of the fingers 29 are retracted by swinging same back on their pivots to the position indicated by the dot and dash line, Fig. 2, and as indicated in the left hand portion of Fig. 1. This permits axial adjustment of the transfer pinions 22 along their respective splined extensions 21 to thereby disconnect said pinions 22 from meshed relation with their associated spur gears 16a, as best indicated in the left hand portion of Fig. 1. After adjustment of the numeral wheels 10 to the prepaid value, the transfer pinions 22 are adapted to be quickly readjusted to their meshed relation with the spur gears 16a. The fingers 29 are then returned to their normal blocking positions, as in Fig. 2, to retain the pinions 22 in their operating positions.

By means of a cover 32 pivoted at 33 on the casing 34, the fingers 29 are retained in their blocking positions, as best indicated in Fig. 2, when said cover is closed. In accordance with postal regulations, the said cover 32 is also properly locked and sealed by the post office official after each value setting operation.

Having described the invention what is claimed is:

1. In resettable value registering mechanism in combination, numeral wheels rotatively supported on a shaft, each numeral wheel including a differential drive therein and having an actuator driven gear and a tens transfer driven gear associated therewith, tens transfer means associated with successive pairs of numeral wheels comprising a Geneva pinion having a splined extension and operatively associated with one numeral wheel, and a transfer pinion having a

splined opening arranged for axial adjustment along the splined extension into or out of mesh with the tens transfer driven gear of the numeral wheel of next higher order, and means to normally retain the transfer pinion in meshed relation with the tens transfer driven gear.

2. In resettable value registering mechanism in combination, numeral wheels rotatively supported on a shaft, each numeral wheel including a differential drive therein and having an actuator driven gear and a tens transfer driven gear associated therewith, tens transfer means associated with successive pairs of numeral wheels comprising a Geneva pinion having an extension and operatively associated with one numeral wheel, and a transfer pinion having a driving connection with and axially adjustable along the extension for movement into or out of mesh with the tens transfer driven gear of the numeral wheel of next higher order, and means to normally retain the transfer pinion in meshed relation with the tens transfer driven gear.

3. In resettable value registering mechanism in combination, numeral wheels rotatively supported on a shaft, each numeral wheel including a differential drive therein and having an actuator driven gear and a tens transfer driven gear associated therewith, tens transfer means associated with successive pairs of numeral wheels comprising a Geneva pinion having an extension and operatively associated with one numeral wheel, and a transfer pinion having a driving connection with and axially adjustable along the extension for movement into or out of mesh with the tens transfer driven gear of the numeral wheel of next higher order, and a blocking element movable into the path of the transfer pinion when the pinion is in mesh with the transfer driven gear to normally retain the transfer pinion in meshed relation with the tens transfer driven gear.

FRANCIS J. ROUAN.
